UNITED STATES PATENT OFFICE.

ALEXANDER G. WILSON, OF CHICAGO, ILLINOIS.

VENTILATOR.

1,028,518.

Specification of Letters Patent.

Patented June 4, 1912.

Application filed November 2, 1910. Serial No. 590,298.

To all whom it may concern:

Be it known that I, ALEXANDER G. WILSON, a citizen of the United States, residing at Chicago, in the county of Cook and State 5 of Illinois, have invented a new and useful Improvement in Ventilators, of which the following is a specification.

My invention relates to an improvement in the class of ventilators in which the 10 suction-action exerted upon the ventilator by the force of air-pressure produced against it operates to withdraw impure air from the interior of a car or other apartment provided therewith.

15 In the accompanying drawings, Figure 1 is a perspective view of my improved ventilator; Fig. 2 is a section on line 2, Fig. 1; Fig. 3 is a section on line 3, Fig. 2, and Fig. 4 is a section like that presented in 20 Fig. 2, but showing a slight modification better adapting the ventilator to be used in a horizontal position.

The ventilator is a box which is best made 25 of sheet-metal, such as galvanized iron; and it may be formed in any desired shape, though it is illustrated in its preferred general rectangular shape. The inner open 30 end 5, or base, shown of rectangular shape and forming the inlet for the air to be withdrawn, is adapted to cover the vent-opening 35 in the roof or other parts of a car (not shown) to which my improved device is more especially adapted to be applied. The outer end 6, as also the two lateral faces 40 7, 7, are closed or imperforate, the end 6 being wider between these faces than the corresponding section of the base 5. The faces 7 are the outer walls which are opposed to the air-pressure produced by running the car in one direction or the other; and while they may be flat or regular, it is best, for the reason hereinafter explained, to form them bulging, and preferably, as 45 shown, each with a central V-shaped section 8. The bases 9 of the faces 7 are built to project outwardly from the narrower ventilator-base 5 to the width between those faces of the end 6, the width of which at right-angles to the faces 7, however, may correspond with that of the open base, as shown. The side walls 10, 10, extending between the base and end 6 are closed or imperforate, and are shaped, by preference, to present the 50 concave outer surfaces shown, for the purpose hereinafter explained. The sides 10 thus form with the faces 7 openings 11 ad-

jacent and at right-angles to the faces. The corresponding lateral edges of the sides 10 adjacent to each face are connected by a wall 12 containing a central longitudinal 60 opening 13, the parts of the wall which flank its contained opening forming deflector-walls 14 preferably of the general V-shape in cross-section illustrated.

The ventilator constructed as shown is 65 more particularly intended to be used on the roof or deck of a car by fastening it through flanges 15 on its base 5 over a vent-opening provided in such roof, or deck; and its position in use may be either vertical, that 70 is with the end 6 uppermost, or horizontal, but always with the parts 7 facing the line of travel of the car. With the device placed vertically and the car provided with it moving in the direction of the arrow at *a* on 75 Figs. 1 and 2, the advance-face 7, by ramming the air, deflects the resultant air-pressure against it with sufficient velocity past the openings 11 adjacent to that face and the relatively rear openings 11, to suck the 80 impure air out of the car through the base 5 into the central ventilator-chamber 16 and out through the openings 13 and 11. As will be seen, the solid or imperforate advance-face 7 creates the suction-action at the openings 11 so that the operation of the device 85 differs from all ventilators of the present class which present openings in their advance-sides for rushing air through them and thus through the ventilator by the motion of the car to suck the impure air out of the latter. It is desirable to provide faces 90 7 of bulging shape, and particularly in the shape illustrated, thereby to more effectively deflect the air-currents past the openings 95 11. It is also advantageous to provide the outer surfaces of the sides 10 of the concave shape shown, since the air-currents in passing them on clearing the advance-openings 11, tend to follow the depressed surfaces 100 of the sides and in clearing the latter, to be deflected outwardly and thus, while being thereby directed from entering the ventilator through the rear openings 11, exert suction at these openings to supplement 105 the suction-action on the corresponding advance-openings. However, the device operates satisfactorily when the sides 10 are flat. The purpose of the angular walls 12 is to avoid the entrance of cinders, dust, rain 110 or snow into the car through the ventilator by wind striking it laterally. The illus-

trated shape, or any other suitable shape of angular cross-section, of these walls, particularly by coöperating with the opposing bulging surfaces of the faces 7, deflects such 5 wind and the objectionable matter carried by it, entering the openings 11 at either side of the device, past the openings 13 and out of the ventilator through the opposite openings 11. However, when the device is 10 used to extend in a horizontal position, as from a vent-opening in a side of the deck of a car running in the direction indicated by the arrow at a' in Fig. 4, the inner wings of the then uppermost V-shaped walls 12 15 should be extended downwardly to some distance over the openings 13, as shown at 14', to afford shields against down-pouring rain, snow, sleet and the like, entering the car through the ventilator by way of 20 the then uppermost openings 11, and deflect such matter to discharge through the lowermost openings 11.

What I claim as new and desire to secure by Letters Patent is:

25 1. A ventilator of the character described, comprising a box having an inlet, imperforate faces having central bulging sections and lateral flat sections extending therefrom, imperforate sides forming between 30 them and said flat sections interposed outlet-openings, and interior deflecting-walls extending between said imperforate faces and connecting the opposite sides at their corresponding lateral edges to form with said 35 sides a chamber within the box open to said inlet, said walls being formed of members of angular cross-section forming openings between them by which said outlet-openings communicate through said chamber with 40 said inlet.

2. A ventilator of the character described, comprising a box having an inlet, imperforate faces having central V-shaped sections and lateral flat sections extending 45 therefrom, imperforate sides forming between them and said flat sections interposed outlet-openings, and interior deflecting-walls joining corresponding edges of said

sides to form therewith a chamber within the box open to said inlet, said walls being 50 formed of members of general V-shape in cross-section forming openings between them by which said outlet-openings communicate with said inlet, and the apexes of 55 said members extending inwardly.

3. A ventilator of the character described, comprising a box provided with an open base, a closed outer end, relatively-opposite imperforate air-ramming and deflecting faces having central bulging sections and 60 lateral flat sections extending therefrom, and relatively-opposite imperforate side-walls forming openings between their edges and those of said faces, and interior deflecting-walls extending between said faces 65 and joining corresponding edges of said side-walls to form therewith a chamber within the box open to said inlet, said deflecting-walls being formed of members of general V-shape in cross-section forming between them 70 openings through which said outlet-openings communicate through said chamber with said inlet.

4. A ventilator of the character described, comprising a box provided with an open 75 base, a closed outer end, relatively-opposite imperforate air-ramming and deflecting faces having central bulging sections and lateral flat sections extending therefrom, and relatively-opposite imperforate side-walls presenting concave outer surfaces and 80 forming openings between their edges and those of said faces, and interior deflecting-walls extending between said faces and joining corresponding edges of said side-walls 85 to form therewith a chamber within the box open to said inlet, said deflecting-walls being formed of members of angular cross-section forming between them openings through which said outlet-openings communicate 90 through said chamber with said inlet.

ALEXANDER G. WILSON.
